UNITED STATES PATENT OFFICE.

HAROLD WILBERFORCE PRICE, OF TORONTO, ONTARIO, CANADA, ASSIGNOR OF ONE-HALF TO ALLAN McPHERSON, OF LONGFORD MILLS, CANADA, AND ONE-HALF TO WILLIAM RUSTON PERCIVAL PARKER, OF TORONTO, CANADA.

AUTOMATIC TRAIN CONTROLLING AND SIGNALING MECHANISM FOR BLOCK-SIGNAL SYSTEMS.

No. 923,297.

Specification of Letters Patent.

Patented June 1, 1909.

Application filed March 21, 1907. Serial No. 363,691.

To all whom it may concern:

Be it known that I, HAROLD WILBERFORCE PRICE, of the city of Toronto, in the county of York, in the Province of Ontario, Canada, have invented certain new and useful Improvements in Automatic Train Controlling and Signaling Mechanism for Block-Signal Systems, of which the following is the specification.

10 My invention relates to improvements in automatic train controlling and signaling mechanism for block signal systems, and the object of the invention is to devise a simple, positive-acting mechanism requiring no control of the engineer and in which the engine signaling device when once released will not reset itself until the brake valve operating mechanism has completed its movement, in which trouble due to leakage of high pressure air cannot effect any improper movement of the brake valve operating device and cannot prevent the signal receiving device from operating when released.

Further objects are to produce a device of 25 this class, which can be readily applied to a standard engineer's brake valve without any alteration of the same and in which there will be no liability of any danger to the engineer by the engineer's brake handle being caused to move too rapidly.

To these ends I have constructed and arranged my invention as hereinafter more particularly explained.

Figure 1, is a side elevation of an engine and portion of a track showing partially diagrammatically the position of portion of the parts involved in my invention as well as the battery connection between the insulated rails, whereby the engine signal receiving mechanism is operated. Fig. 2, is an enlarged perspective detail of the engine signal receiving mechanism. Fig. 3, is a longitudinal vertical section through the valve chest on the plane of the whistle valve.

40 Fig. 4 is a sectional view of the valve chest partially broken away and in section to show the passage-ways. Fig. 5, is a cross section of the valve chest shown in Fig. 2. Fig. 6, is an enlarged perspective detail of the valve chest of the engine signal receiving mechanism partially broken away and in section and showing the pipe connection to the adjustable automatic controller of service braking

force, which is shown in section and to the brake valve operating device. Fig. 7, is a detail of the cushion retarder for the trip arm of the engine signal receiving mechanism. Fig. 8, is a perspective view showing the brake valve operating device and its connection to the engineer's brake valve. Fig. 9, is a vertical section through the brake valve operating device. Fig. 10, is a view partially broken away and in section of the brake valve operating device. Fig. 11, is a perspective detail of the cushioning piston used in the brake valve operating device. Fig. 12, is a detail of the ring, which is operated to throw the engineer's brake valve into the brake applying position. Fig. 13 is a detail view of the arm M.

In the drawings like characters of reference indicate corresponding parts in each figure.

In order that my invention may be readily understood in all its details I show diagrammatically in Fig. 1, a locomotive in which are located the several parts of my apparatus and parts involved in my invention comprising the engine signal receiving device A, the engineer's brake valve B and automatically operating device C therefor, the adjustable automatic controller D of the service braking force and the main air reservoir of the engine and the pipe and electrical connections hereinafter described. The signals are set on the track against a train by the relays, such as described in an application for improvements in an automatic electric block signal system filed March 21st, 1907, under Serial Number 363,690, causing a battery F to be connected to the rails as indicated in Fig. 1, the terminals of the battery being separated by insulated rail joints F'.

The front truck E of the locomotive is insulated from the main body thereof by any suitable insulating device, such as a plate E'. It will, therefore, be seen that both the front truck and the main driving wheels are electrically separate except when connected together by continuous rails or by wire in the engine. If found preferable, of course, the engine may be electrically separated from the tender instead.

The engineer's brake valve B is connected by the pipe G to the main air reservoir 2

and by the pipe G' to the train line G^2 , which leads to the cylinders G^3 by which the brakes are applied to the main wheels of the engine. The train line, of course, leads also to the reservoir and other cars of the train.

Of the various mechanisms involved in my invention I shall first describe the engine signal receiving device.

10 H is a valve chest.

I are a pair of magnets supported on a suitable standard J on the base J' of insulating material.

15 K are a pair of magnets supported on a suitable standard K' and base J' .

3 is a wire leading from the magnet I to the binding post $3'$ connected to the main body of the engine.

4 is a wire leading from the opposite end 20 of the magnet I to the truck.

25 5 is a wire leading from the wire 4 to the magnet K and 6 is a wire leading from the magnet K to and through the battery 7 to the binding post 8, see Figs. 1 and 2.

29 9 is a branch wire leading from the wire 4 to the binding post I' on the armature I^2 of the magnet I.

30 The armature I^2 is supported in suitable bearings on the standard J and is connected by a spring I^3 to the standard.

35 K^2 is an armature pivoted on the bottom of the standard K' and connected by a spring K^3 to the standard. The upper end of the armature K^2 has a bent end K^4 as indicated and the armature is designed to co-act as will be readily understood with the magnets K.

40 L is a cylinder secured to the base J' , see Figs. 2 and 7.

45 L' is the cap of the cylinder, which is provided with a depending flange L^2 , one side being deeper than the other.

50 L³ is a piston having a rod L^4 , which extends through a slot 10, the upper end of which is designed to form a retarding stop as will hereinafter appear. The piston L^3 is supported in the upper position by a spiral spring L^5 .

55 L⁶ is a set screw, which extends through a lug L^7 forming part of the cap L' and designed to abut the rod L^4 and adjust it to a more or less vertical position to co-act with the arm M.

55 H' is a bearing bracket forming part of the valve chest H and H² is an arbor journaled in the bracket and upon which the arm M is secured. The arm M normally rests upon the extremity of the bent end K^4 of the armature K^2 .

60 H³ is a pinion secured on the arbor H^2 and H⁴ is a stop for the arm M secured on the bracket H'.

65 H⁵ is a drum secured on the arbor H^2 and having located thereon the spiral spring H^6 , one end of which is fastened to the drum and

the other to the bracket H', the normal tendency of the spring being to force the arm M in the direction indicated by arrow. One flange of the drum H^5 is provided with a ratchet notch H^7 in which normally rests 70 the bent end of the lever H^8 , which is fulcrumed on the bracket 11, at the top of the cylinder H^9 , which communicates with the interior of the valve chest H. The piston H^{10} is located in the cylinder H^9 and is normally held at the upper end of the annular enlargement H^{11} by the spiral spring H^{12} , see Fig. 3, so as to close the passage of the air from the valve chest H. The rod 13 of the piston H^{10} extends up underneath the 80 end of the lever H^8 .

14 is a pipe or tube leading from the cylinder H^9 to the air whistle 15.

Upon the arm M being thrown down in the manner, which will hereinafter appear, 85 the bent end of the lever H^8 is raised out of the notch H^7 and thereby depresses the piston and establishes communication between the air chest and the whistle and thereby apprising the engineer of the approaching 90 danger and also of the fact that the application of the brakes is being started. The air chest receives the air from the main air reservoir 2 through the pipe G hereinbefore referred to.

95 N is an arm secured on the end of the arbor N' and provided with a quadrantal end N^2 , which meshes with the pinion H^3 .

O is a cylinder located in the top of the valve chest and provided with a piston O' , 100 which is connected by a link O^2 to a fork N^3 on the arm N.

105 O³ is a pipe leading from the bottom of the cylinder O to the passage-way O^4 leading to the port O^5 at the bottom of the valve chest, see Figs. 4, 5 and 6.

110 O⁶ is a pipe leading from one side of the cylinder O to the passage-way O^7 communicating with the port O^8 at the bottom of the valve chest H. The pipe O^6 leads at the cylinder end into a valve chamber O^9 , which communicates by a passage-way O^{10} to the cylinder O. A set screw 16 is provided to limit the size of the passage-way O^{10} . One 115 end of the passage-way is provided with a ball valve 17, which is held to normally close the passage-way O^{10} by means of the spiral spring 18. It will thus be seen that the valve 17 forms practically a check valve, so that the air can only pass outwardly from 120 the cylinder O into the pipe O^6 .

125 O¹¹ is a port located on a line with the port O^8 and O¹² is a port located on a line with the port O^6 . The ports O^{11} and O^{12} are connected by a passage-way 19.

P and Q are slide valves suitably held in the bottom of the chest H. The slide valve P is provided with the lugs P' into which extends the arm N^4 secured on the arbor N' and by which the slide valve is operated as 130

will hereinafter appear. The slide valve P is provided with a bottom port P^2 , which is designed to co-act with the ports O^8 and O^{11} in the bottom of the valve chest. The slide valve P is also provided with a port P^3 designed to co-act with the port O^8 as will hereinafter appear and with a bottom port P^4 designed to co-act with the ports O^{13} and O^{14} and a port P^5 designed to co-act with the port O^{14} . The slide valve Q is provided with a connecting port Q' designed to co-act with the port O^{12} and the port O^{15} , which communicates with the atmosphere, and with the connecting port Q^2 which co-acts with the ports O^5 and O^{16} and with a port Q^3 , which co-acts with the port O^5 .

Q^4 is an arm secured on the arbor Q^5 . The arm Q^4 engages with the lugs Q^6 on the slide valve Q . One end of the arbor Q^5 extends through the side of the valve chest H and is provided with a controlling handle Q^7 , which is designed to be operated by the engineer in order to retard or stop the operation of the engineer's brake valve as will hereinafter appear. The device by which this is accomplished I shall now describe.

B' is the brake valve handle. The brake valve has at the upper end a flange B^2 , which has a cut-away portion, the ends of which form stops for the brake handle.

R is the main casing of the brake valve operating device, which is provided with a lower flange R' and a supplemental casing R^2 affixed thereto and provided with a lower segmental flange R^3 . This segmental flange R^3 has an internal groove R^4 and beneath it extends a segmental ring R^5 with a corresponding groove. By means of bolts R^6 extending through these rings the casing R is fastened to the top flange B^2 of the engineer's brake valve. The casing R is connected by the pipe S leading from the top thereof to the port O^8 of the valve chest H .

S' is a pipe, which leads from the casing R at a point below the pipe S to the top of the casing T' of the controller D by which the brake valve is held in service position until the brakes are applied sufficiently as will hereinafter appear.

S^2 is a pipe which leads from the casing T' at a point intermediate of its height to the port O^{16} at the bottom of the valve chest H . The supplemental casing R^2 serves to close the bottom of the casing R and is provided with an orifice R^7 .

19^1 is an internal cylinder provided with a bottom 20 and a base 21 , which is held on the top of the supplemental casing R^2 . 22 is a ring, which surrounds the base 21 and has a projection 23 at one side thereof, which depends through a slot 24 in the top of the supplemental casing R^2 . The cylinder $19'$ is filled with oil and the top is provided with a disk 25 provided with holes 26 . A

supplemental disk 27 is provided, which is connected to the disk 25 by the stems 28 having the tops 29 between which and the disks 25 extend spiral springs 30 . The disk 25 is provided with a stem 31 at the upper end of which is a piston 32 . Between the piston 32 and the base 21 of the cylinder 19 I provide a spiral spring 33 , which has a normal tendency to hold the disk 32 in the uppermost position.

Supported on the disk 32 is a supplemental piston 34 , which is held by the spring 33 normally against the top of the cylindrical casing R .

Upon the air passing in through the pipe S on to the top of the piston 32 the disk 25 is forced downwardly and the disk 27 forced against the lower face of the disk 25 , thereby closing the holes 26 . The disk 25 , however, is of such a fit that it permits of a leak around its edge and consequently oil will escape above it, but it will serve to prevent too rapid downward movement of the piston 34 . Upon the return stroke the oil passes back through the holes 26 , the disk 27 being forced away by the oil pressure and compressing the springs 30 .

The piston 34 is provided with a downwardly extending projection 35 having the sides inclined as indicated and designed to abut the projection 23 .

I shall now describe the controlling device D .

T^2 is a piston, the stem or rod of which is provided with a disk T^3 at its lower end. 100 Underneath the disk T^3 I provide a disk valve T^4 held against the disk T^3 by means of the stem T^5 having a suitable head and a spring T^6 extending between the disk T^3 and the head of the stem T^5 . The valve T^3 105 covers a hole T^7 .

T^8 is a by-pass extending from the bottom of the casing T' to a point above the uppermost position of the disk T^3 .

T^9 is a needle valve, which extends into the pass where it runs upwardly from the horizontal portion as indicated.

T^{10} is a spring extending between the bottom of the casing T' and the disk T^3 . The needle valve T^9 may be adjusted as desired. 110 The casing T' is partially filled with oil as indicated in the drawing to a point above the level of the top of the by-pass. The spring T^{10} normally forces the piston upward until the air is exhausted above the piston.

T^{11} is a hole located normally opposite the reduced portion of the piston and is designed to allow of the air leaking past the piston T^2 to pass into the atmosphere instead of passing into the pipe S' .

The downward movement of the piston T^2 is adjustably retarded by the oil immersed disk T^3 and by the by-pass T^8 . The check valve T^4 closes the hole T^7 to prevent

the oil passing upwardly through the disk T³ when the piston T² is being forced downwardly.

Having now described the construction and arrangement of the various devices in detail involved in the operation of my automatic train controlling and signaling apparatus I shall now describe the operation of the parts to perform the various functions necessary to control the engineer's brake valve to apply the brakes when acting in conjunction with the track relays hereinbefore briefly referred to.

The locomotive when passing over the block junction where a signal is set against it will not before the forward trucks pass over the insulating joint F' affect the mechanism in the cab for the reason that there is no battery in the circuit. As soon, however, as the forward truck passes over the insulating joint a circuit is completed through the battery F of the relay and the rails on each side of the insulating joint, the truck E, the wire 4', the engine frame and wire 3 to the magnet I. The result is that the armature I² is drawn to the contact 8 and a circuit established through the wire 6, battery 7, magnet K, wires 5 and 9 and armature I² and contact 8. The result is that the armature K² is drawn to the magnet K, thereby withdrawing the bent end K⁴ from underneath the arm M, which is thereby caused to turn striking in its descent the rod L⁴, which retards it according to the position that the rod is set while the arm is forcing the rod out of its path as the piston of the rod descends as hereinbefore described.

As the arm passes downwardly the whistle lever H⁸ operates to blow the whistle, thereby apprising the engineer of danger. At the same time that the arm M turns the gear H³ throws the quadrant N² upwardly until the arm has made a half revolution and comes in contact with the stop H⁴.

By the movement of the quadrant N² the piston O' is pushed inwardly as indicated. The arm N⁴ is also moved from the position shown in full lines in the drawing to the position shown by dotted lines, thereby bringing the port P³ opposite the port O⁸ and thus causing the air under pressure in the valve chest to pass down through the pipe S into the top of the casing R forcing the spring held-piston 34 down and causing its downwardly extending wedge-shape projection 35 to force the ring 22 and consequently the projection 23 and the brake handle B' of the engineer's brake valve into service position.

It is sometimes desirable when the handle B' of the engineer's brake valve is forced into service position that it be maintained in such position a sufficient length of time in order to adequately apply the brakes and

this is accomplished by the casing T' and 65 its parts as the air passes out through the pipe S' and before it can reach the pipe S² the piston T² has to move downwardly as hereinbefore described and this gives the desired period of time to apply the brakes. 70 This period may be regulated by the set screw T⁹ as hereinbefore referred to.

When the air has reached the pipe S² it passes upwardly through the port O¹⁶ and connecting port Q² port O⁵ passage-way O⁴ 75 and pipe O³ to the cylinder O, thereby forcing back the piston O' and restoring the arm N and consequently the arm M and whistle lever H⁸ to their normal position.

In case there should be any leakage of air 80 around the ports of the slide valve Q which air might pass through the pipe O³ and accumulate behind the piston O' in the cylinder O and thereby prevent the free operation of the piston O' on receipt of the signal, 85 such air instead of accumulating would pass through the port Q², port O¹⁶ and pipe S² around the reduced portion of the piston T² and out through the port T¹¹ to the atmosphere. 90

I have shown ports O¹¹ and O¹⁴ at the bottom of the valve chest designed to 95 contact with the connecting ports P² and P⁵. I have not shown, however, any device operated therefrom, but it is my intention if found desirable to use these ports with suitable air controlled devices to operate the throttle valve of the engine. I have shown them to exemplify the adaptability of my device for various purposes necessary in a 100 signaling apparatus.

Should the engineer desire not to have the 105 brake valve operate he may easily prevent it by grasping the handle Q⁷ and throwing the slide valve Q in the direction indicated by arrow in Fig. 3, thereby throwing the port Q³ opposite the port O⁵ thus allowing the air to escape through the port O⁵, passage-way O⁴ pipe O³ to the cylinder O, thus forcing the piston O' back and stopping the 110 operation of the parts, which affect the engineer's brake valve. Should the engineer however, hold his hand on the handle Q⁷ in order to permanently hold the piston O' forward by air pressure and thus prevent the arm M dropping on receipt of the signal, I can prevent such action being taken, by making it involve applying the brakes, for the reason that the air from the cylinder O will then pass outwardly through the pipe O⁶ into the port O⁸ of the pipe S, into the top of the casing R thereby applying the 115 brakes as hereinbefore described.

The path of air through the port O¹¹, the 120 passage way 19, port O¹², port Q' and port O¹⁵ to the atmosphere, will be necessarily closed, on account of the engineer holding his hand on the handle after having shifted

the valve. Consequently the passage of air must be through the pipe S hereinbefore referred to.

What I claim as my invention is:

5. 1. In an automatic train controlling and signaling system of the class described, the combination with the engineer's brake valve and handle thereof, of an electrically started air operated and controlled service application means, as specified.

10. 2. In an automatic train controlling and signaling system of the class described, the combination with the engineer's brake valve and handle thereof, of an electrically started air operated and controlled service application means, and a retarding device in the air operated means, as specified.

15. 3. In an automatic train controlling and signaling system of the class described, the combination with the engineer's brake valve and handle thereof, of an air operated means for throwing the handle into the service position, a main air reservoir, a valve chest and valve therein, a pipe leading from the main air reservoir to the valve chest, a pipe leading from the valve chest to the air operating means of the handle a discharge pipe for the air operating means and a retarding device in the path of said discharge pipe as 20 and for the purpose specified.

25. 4. In an automatic train controlling and signaling system of the class described, the combination with the engineer's brake valve and handle thereof, of an air operated means for throwing the handle into the service position, a main air reservoir, a valve chest and valve therein, a pipe leading from the main air reservoir to the valve chest, a pipe leading from the valve chest to the air operating means of the handle, a discharge pipe for the air operating means, a retarding device in the path of said discharge pipe and a pipe leading from the retarding device to the valve chest and mechanism co- 30 acting therewith for restoring the valve to normal as and for the purpose specified.

35. 5. In an automatic train controlling and signaling system of the class described, the combination with the engineer's brake valve having an upper circumferential flange, and the handle thereof, of a superimposed cylindrical casing, a supplemental casing secured to the bottom flange thereof forming a bottom for the main casing and having a 40 cut-away portion and bottom flange to fit on the top flange of the engineer's brake valve, a supplemental flange fitting under the aforesaid flanges and bolted to the bottom flange of the supplemental casing as and for the purpose specified.

45. 6. In an automatic train controlling and signaling system of the class described, the combination with the engineer's brake valve having an upper circumferential flange, and the handle thereof, of a superimposed cy-

lindrical casing, a supplemental casing secured to the bottom flange thereof forming a bottom for the main casing and having a cut-away portion and bottom flange to fit on the top of flange of the engineer's brake valve, a supplemental flange fitting under the aforesaid flanges and bolted to the bottom flange of the supplemental casing, air inlet and outlet ports at the top of the casing and means within the casing operated by air pressure for throwing the handle of the engineer's brake valve into service position, as and for the purpose specified.

50. 7. In an automatic train controlling and signaling system of the class described, the combination with the engineer's brake valve and handle thereof, of a superimposed cylindrical casing and supplemental casing connected thereto, and means for securing the supplemental casing to the top of the engineer's brake valve, air inlet and outlet ports at the top of the casing, and means within the casing operated by air pressure for throwing the handle of the engineer's brake valve into the service position, as and 55 for the purpose specified.

55. 8. In an automatic train controlling and signaling system of the class described, the combination with the engineer's brake valve and handle thereof, of a superimposed cylindrical casing, a supplemental casing to the top of the engineer's brake valve, air inlet and outlet ports at the top of the casing and means within the casing operated by air pressure for throwing the handle of the 60 engineer's brake valve into the service position a ring having a depending projection extending through the slot in the top of the supplemental casing, an internal cylinder designed to contain oil and provided with a 65 suitable base around which the aforesaid ring fits, the spiral spring surrounding the internal cylinder, a piston and stem and disk secured to the bottom of the stem and provided with a spring held disk valve and outer piston supported on the top of the aforesaid piston and provided with a depending projection on the ring, as and for the purpose specified.

70. 9. In an automatic train controlling and signaling system, of the class described, the combination with the engineer's brake valve and handle thereof and air operated means for shifting the handle, and the valve chest, and valve for controlling the admission of air into the air operated means of a retarding device located in the air outlet pipe of the air operated means and between such means and the valve chest as and for the purpose specified.

75. 10. In an automatic train controlling and signaling system of the class described, the combination with the engineer's brake valve and handle thereof and air operated means for shifting the handle, and the valve chest,

- and valve for controlling the admission of air into the air operated means, of a cylinder connected at the top by a pipe to the outlet of the air operated means, of and a pipe leading from said cylinder below the level of the aforesaid pipe to the valve chest, and a piston located in said cylinder and provided with a disk and spring controlled valve in such disk, and a by-pass from above 5 the top of the disk to the bottom of the cylinder provided with a needle valve, the said cylinder being arranged to contain fluid as and for the purpose specified. 10
11. In an automatic train controlling and signaling system, of the class described, the combination with the engineer's brake valve and air operated means for placing the brake valve in the service position, and the valve chest for controlling the admission of 15 the air to the air operated means, of means for operating the valves in the valve chest and electric control for such means operated from a relay connected to the rails, as and for the purpose specified. 20
12. In an automatic train controlling and signaling system of the class described, a controlling device for the air operated means of the engineer's brake valve handle comprising a valve chest having a pipe communicating with the air reservoir and ports in the bottom thereof alined with each other, one communicating with an air operated means for shifting the brake valve handle and the other communicating normally with the atmosphere, a slide valve provided with a port and means for shifting the slide valve to bring the port therein opposite the port leading to the air operated means as and for the purpose specified. 25
13. In an automatic train controlling and signaling system of the class described, a controlling device for the air operated means of the engineer's brake valve handle comprising a valve chest having a pipe communicating with the air reservoir and ports in the bottom thereof alined with each other, one communicating with an air operated means for shifting the brake valve handle and the other communicating normally with the atmosphere, a slide valve provided with a port, means for shifting the slide valve to bring the port therein opposite the port leading to the air operated means and electrically operated means for controlling the movement of the aforesaid means as and for the purpose specified. 30
14. In an automatic train controlling and signaling system of the class described, a controlling device for the air operated means of the engineer's brake valve handle comprising a valve chest having a pipe communicating with the air reservoir and ports in the bottom thereof alined with each other, one communicating with an air operated means for shifting the brake valve 35
15. In an automatic train controlling and signaling system of the class described, the combination with the arbor from which the slide valve is directly operated and the arm secured on the end of the same and provided with a toothed quadrantal end, and an arbor journaled in suitable bearings, and a pinion and arm carried thereby, of a magnet having a spring-pressed armature, the upper end of which normally holds the arm on the arbor carrying the pinion in its normal position, a circuit closing magnet carried on a suitable standard, and armature thereof, and contact for one end of the armature, a local battery and a wire connecting the contact and extending from the battery, and the arm controlling magnet back to the circuit closing magnet, and a wire leading from the rail to the armature of the circuit closing magnet as and for the purpose specified. 40
16. In an automatic train controlling and signaling system of the class described, the combination with the arbor journaled in bearings on the valve chest and means for operating the valve in the chest therefor and an arm on the end of such arbor, and the magnet and armature for normally holding such arm in the normal position of a fluid cylinder and spring-pressed piston therein having the rod thereof extending through a slot in the top of the cylinder designed to have the top thereof co-act with the end of the arm aforesaid as and for the purpose specified. 45
17. In an automatic train controlling and signaling system of the class described, the combination with the valve chest and arbor journaled in bearings at the outside thereof and having an arm at one end thereof, and electrically operated means for holding such arm in the normal position, of a drum secured on the arbor and having one of the flanges thereof provided with a notch, a spring surrounding the drum suitably connected thereto and to a portion of the frame, a cylinder extending upwardly from the valve chest and communicating therewith and having an annular enlargement, an air whistle and a pipe leading from the cylinder to the air whistle, a piston located in the 50
- 55
- 60
- 65

cylinder and the rod extending through the top thereof, a spring for normally holding the piston on its seat and a lever suitably fulcrumed and having one end extending 5 over the piston rod and the opposite end extending into the notch in the flange of the drum as and for the purpose specified.

18. In an automatic train controlling and signaling system of the class described, an 10 air controlling apparatus for the air operated means for shifting the engineer's brake valve handle comprising a valve chest communicating with the main air reservoir and having two alined ports in the bottom to 15 ward one side and four alined ports in the bottom toward the opposite side, the two end ports of the two sets being connected by a passage-way and the two next ports communicating one with the air operated means and 20 the other with the atmosphere, a slide valve having a port extending therethrough and a connecting port co-acting with the two ports on the one side, a supplemental slide valve provided with means for operating the same 25 and having two connecting ports co-acting each with a pair of the four alined ports, an arbor suitably journaled in the valve chest and operatively connected to the slide valve on the inside of the chest, an arm located on 30 the arbor on the outside of the chest provided with a quadrantal end, a supplemental arbor provided with an arm suitably controlled and a pinion meshing with the quadrantal end of the outside arm, a piston located 35 on the top of the valve chest and a link connecting the piston to the quadrantal arm, a pipe leading from the piston to a passage-way extending through the side of a valve communicating with the port at the opposite end of the four alined ports, a pipe connecting the port next the end with 40 the piston and a spring-pressed check valve designed to normally close the communication between such pipe and the piston as and for the purpose specified.

19. In an automatic train controlling and signaling system of the class described, an air controlling apparatus for the air operated means for shifting the engineer's brake valve handle comprising a valve chest communicating with the main air reservoir and having two alined ports in the bottom toward one side and four alined ports in 45 the bottom toward the opposite side, the two end ports of the two sets being connected by a passage-way and the two next ports communicating one with the air operated means and the other with the atmosphere, a slide 50 valve having a port extending therethrough and a connecting port co-acting with the 55

two ports on the one side, a supplemental slide valve provided with means for operating the same and having two connecting ports co-acting each with a pair of the four alined ports, an arbor suitably journaled in the valve chest and operatively connected to the slide valve on the inside of the chest, an arm located on the arbor on the outside of the chest provided with a quadrantal end, a supplemental arbor provided with an arm suitably controlled and a piston meshing with the quadrantal end of the outside arm, a piston located on the top of the valve chest and a link connecting the piston to the quadrantal arm, a pipe leading from the piston to a passage-way extending through the side of a valve communicating with the port at the opposite end of the four alined ports, a pipe connecting the port next the end with 60 the piston and a spring-pressed check valve designed to normally close the communication between such pipe and the piston as and for the purpose specified. 65

20. In an automatic train controlling and signaling system, of the class described, the combination with the valve chest, an arbor journaled in bearings at the outside thereof, and having an arm at one end thereof, and electrically operating means holding, when 70 deenergized, such arm in the normal position, of a whistle operating means connected to the arbor, to be operated upon the commencement of the downward movement of the arm before the valves are opened, as and 75 for the purpose specified.

21. In an automatic train controlling and signaling system of the class described, the combination with the engineer's brake valve and handle thereof, of an automatic device 80 so formed as to remain stationary when the brake valve handle is operated and designed to be operated to control the handle to set a service or graduated stop as specified.

22. In an automatic train controlling and 85 signaling system of the class described, the combination with the engineer's brake valve and handle thereof, of an automatic device so formed as to remain stationary when the brake valve handle is operated and designed 90 to be operated to control the handle to set a service or graduated stop and yet leave the emergency stop controllable as specified.

HAROLD WILBERFORCE PRICE.
